LOADING APPARATUS

Timothy F. McCarthy, Indiana, Pa.

Application June 4, 1941, Serial No. 396,507

11 Claims. (Cl. 198—220)

This invention relates to improvements in loading apparatus, and more particularly relates to a novel form of loading apparatus actuated by a shaker conveyer, for loading material, such as coal, from the working face in mines.

The principal objects of my invention are to provide a loading device adapted to extend along the working face of a mine and pick up the mined material and load it onto a main conveyer disposed at an angle to said loading device, and forming a drive means for the loading device.

A more specific object of my invention is to provide a shaker conveyer loading pan disposed at an angle to the main trough line and driven therefrom and communicating therewith, together with means for driving the loading pan from the main trough line and means for advancing the pan into the material it is desired to load.

Other objects of my invention will appear from time to time as the following specification proceeds and with reference to the accompanying drawings wherein:

Figure 1 is a plan view of a loading device constructed in accordance with my invention;

Figure 2 is an enlarged fragmentary view in side elevation of the forward part of the conveyer trough line, with certain parts shown in substantially longitudinal section;

Figure 3 is a sectional view taken substantially along line 3—3 of Figure 1;

Figure 4 is a sectional view taken substantially along line 4—4 of Figure 1;

Figure 5 is a sectional view taken substantially along line 5—5 of Figure 1;

Figure 6 is a sectional view taken substantially along line 6—6 of Figure 1;

Figure 7 is a sectional view taken substantially along line 7—7 of Figure 1;

Figure 8 is an enlarged fragmentary detail plan view of a portion of the advancing mechanism, with certain parts broken away and certain other parts shown in horizontal section, in order to show certain details of the means for advancing the device of my invention; and

Figure 9 is an enlarged sectional view taken substantially along line 9—9 of Figure 8.

Referring now to the embodiment of my invention illustrated in the drawings, a reciprocating trough section 10 on the forward end of a shaker conveyer pan line is transversely pivoted at its forward end on a ball frame 11. Said pan line is reciprocably driven by a suitable drive mechanism (not shown) in a usual manner, for conveying material away from the working face of a

mine. An inclined extensible trough section 12, having a flared flattened forward end 13 adapted to rest on the ground, is nested within and is mounted for extension from said reciprocating trough section.

The ball frame 11 may be of any well known form and is adapted to be held in position on the ground by means of the usual form of screw jacks 14, 14, adapted to be interposed between said 10 frame and the mine roof. Said ball frame, as herein shown, includes facing races 15, 15 for balls 16, 16. Said races are herein shown as being of a semi-cylindrical formation, so arranged as to hold the upper slideable portion of said ball 15 frame from lateral displacement with respect to the stationary portion of said ball frame.

The extensible trough section 12 is detachably secured to the reciprocating trough section 10, for extension or retraction with respect thereto, by 20 means of a pair of C-clamps 24, 24 (see Figure 5). Said C-clamps are herein shown as being secured to the undersides of flanges 25, 25, projecting laterally from the upper ends of the side walls of said reciprocating trough section. Members 26, 26 are threaded in the upper portions of said 25 C-clamps and are adapted to hold flanges 27, 27, projecting laterally from the upper end of the side walls of said extensible trough section, in engagement with the flanges 25, 25.

30 A guide means is provided for the extensible trough section 12, for guiding said extensible trough section against lateral displacement during extension or retraction thereof and during reciprocation of the conveyer. As herein shown, said guide means includes a channel 29 adapted to extend along one rib of the working place, closely adjacent thereto, and supported above the ground on screw jacks 30, 30 at its ends. The channelled portion of said channel opens in an upward direction and is adapted to be engaged by a roller 31, depending from an arm 32 projecting laterally from said extensible trough section. Said arm, as herein shown, extends along the bottom of said extensible trough section, and 40 upwardly along an outer side thereof for a portion of the height of said side, and outwardly therefrom towards the channel 29 in a horizontal direction (see Figures 1, 2 and 5).

Referring now in particular to certain novel 50 features of the means for picking up mined material from the working face and transferring it onto the main pan line, a corner pan 23 is pivotally connected to and communicates with the forward end of the extensible trough section 12. Said corner pan, as herein shown, is adapted to

slidably rest on the ground and is provided with an arcuately formed inner retaining wall 33. A swingable controlling arm 34 is provided to mount said corner pan for pivotal movement along the ground about a fixed vertical axis.

The connection between the extensible trough section 12 and the corner pan 23, for reciprocably driving said corner pan, includes a bracket 35 extending inwardly from a side wall of the forward flared portion 13 of said extensible trough section, and overlapped by a member 36 extending outwardly from the retaining wall 33. A pivotal pin 37 pivotally connects said connecting member with said bracket. A connecting flange 38 projects outwardly from the opposite end of said retaining wall and forms a means for connecting the opposite end of said corner pan with a bracket 39 projecting from a retaining wall 41 of a loading pan 44, herein shown as extending parallel to the working face and perpendicular to said extensible trough section.

The horizontally swingable controlling arm 34 is herein shown as being vertically pivoted to the forward end of an advancing member 45, herein shown as including an I-beam 46 extending longitudinally of said extensible trough section and slidably guided in supporting and guiding members 47 and 48.

The controlling arm 34 is vertically pivoted between brackets 49 and 50, projecting forwardly of the I-beam 46, on a bushing 51 mounted on said bracket members and having a convex bearing surface adapted to form a bearing for said controlling arm, to permit limited vertical movement of said arm as well as horizontal swinging movement thereof. The opposite end of said controlling arm is transversely pivoted between two spaced pairs of spaced apart supporting ears 52, 52, projecting inwardly of the retaining wall 33.

The outer side of the corner pan 23 includes an advance agitating edge 54 and a side agitating edge 55 joining said advance edge at an angle. Said agitating edges are herein shown as being serrated, to permit said corner pan to more readily agitate and pick up the loose material from the ground.

A retaining side board 56, having an advance serrated agitating edge 57, is adapted to be detachably secured to the side agitating edge 55 of said corner pan (see Figure 1). Said retaining side board is provided with a side retaining wall 58 and is attached to said corner pan by means of spaced connecting members 60, 60, projecting from the side thereof, opposite from the retaining wall 58 and extending within suitable apertured portions of the side agitating edge 55. Nuts and bolts 61, 61, may be provided to connect said connecting members to said corner pan (see Figure 7).

The loading pan 44 has a flat bottom adapted to slidably rest on the mine bottom, and has an advance agitating edge 73, opposite from the retaining wall 41. Said agitating edge is herein shown as being serrated and is adapted to be advanced into and agitate the material for loading it onto said loading pan. Said loading pan is pivotally connected to said corner pan by means of the connecting flanges 38 and 39 and is reciprocably guided by a ball frame 75 secured to the rear side of the retaining wall 41 and projects rearwardly therefrom. Said ball frame, as herein shown, includes an H-shaped member 76 secured to and extending along the retaining wall 41 and having the web thereof projecting rear-

wardly from said retaining wall in a horizontal direction. Balls 77, 77 engage the upper and lower sides of the web of said H-shaped member and are interposed between said web and the insides of a channelled supporting and guiding member 78, within which said H-shaped member extends. Said channelled supporting and guiding member is mounted on a block 79 supported on a shoe 80 by means of a threaded shaft 81, for vertical adjustment (see Figure 6). Said block in turn is pivotally connected to the forward end of an advancing member 82, by means of a pivotal pin 83. Said advancing member is herein shown as being an I-beam 84 supported in supporting and guiding members 85 and 86, for longitudinal movement with respect thereto.

The loading pan 44 has a connecting ear 87 projecting from the end thereof opposite from the corner pan 23, and adapted to have a loading pan 88 detachably connected thereto. As herein shown, said connecting ear extends outwardly and forwardly from the retaining wall 41 and is adapted to be overlapped by a connecting ear 89, projecting rearwardly from a retaining wall 90 of the loading pan 88. A plurality of apertures are provided in said connecting members to permit one pan to be hinged with respect to the other, or to permit both loading pans to be rigidly connected together. The loading pan 88 is of the same construction as the loading pan 44, and is abutted at its end opposite from said loading pan 44 by a ball frame 91, connected to the end of an advancing member 92. Said advancing member includes an I-beam 93 guided in supporting and guiding members 94 and 95, similar to the supporting and guiding members 47 and 48, and 85 and 86. Said loading pan 88 has a connecting ear 96, forming a means for connecting a loading pan 97 thereto, for extending said loading pan in accordance with the width of the working face, as desired.

The advancing members 45, 82 and 92 are each mounted in a similar manner and are advanced by similar advancing mechanism, so the advancing member 45 only will herein be described in detail. As herein shown, the supporting and guiding member 47 is held in position on the ground by means of spaced apart jacks 98 and 99, interposed between said supporting and guiding member and the mine roof. A roller 100 engages the underside of the web of the I-beam 46 and forms a support for said I-beam. Longitudinally spaced rollers 101, 101 are adapted to engage the side of said I-beam adjacent the extensible trough section 12 and a roller 102 is adapted to engage the opposite side of said I-beam.

The supporting and guiding member 48 has a horizontal roller 103, which is adapted to be engaged by the underside of the web of the I-beam 46, to form a rolling support therefor. Said supporting and guiding member is provided with longitudinally spaced vertical rollers 104, 104, adapted to engage the side of said I-beam adjacent said extensible trough section. Said supporting and guiding member is likewise provided with a cylindrical column 105 having a roller 106 journaled thereon and adapted to engage the side of said I-beam opposite from the rollers 104, 104 (see Figure 9). Said column has a threaded shaft 107 threaded therein and having suitable means on the upper end thereof (not shown) for engaging the mine roof, to hold said supporting and guiding member in po-

sition. A jack 108 is adapted to engage the opposite side of said supporting and guiding member to aid in holding it in position on the ground. A motor 109 is mounted on said column and drives a worm gear 110, journaled coaxially of said column 105, by means of a worm 111 on a longitudinal motor shaft 112. Said worm gear is provided with a depending hub 113, to which is keyed a winding drum 114. A cable 115 is secured at its forward end to a 10 connecting member 116, projecting outwardly from the forward end of said I-beam. Said cable is trained rearwardly from said connecting member and is wrapped around said winding drum. From said drum it extends to the rear end of said I-beam and is connected to a connecting member 117 projecting outwardly from the rear end of said I-beam. Thus, when power is applied to said motor, to start said motor, said I-beam will be moved along said supporting and guiding members, to advance the corner pan 23 and extensible trough section 12 towards the working face, and when the direction of rotation of said motor is reversed, said corner pan and extensible trough section will be moved in a direction away from the working face.

In a like manner, the I-beam 84 of the advancing member 82 has a flexible feeding member 118 connected to opposite ends thereof and wrapped around a winding drum 119 on the supporting and guiding member 85. A motor 120 is provided to drive said winding drum in a manner similar to which the motor 109 drives the winding drum 114.

The advancing member 92 is likewise advanced by a flexible feeding member 121 wrapped around a winding drum 122 and secured at its ends to the I-beam 93. Said winding drum is driven by a motor 123 in the same manner that the winding drum 114 is driven from the motor 109. The motors 109, 120 and 123 may be connected together to be operated simultaneously by means of a push-button control, for advancing the corner pan 23 and extensible trough section 12 with the loading pans 44 and 88. Said motors may also be operated independently, if desired, to provide a free range of adjustment of said loading pans and corner pan with respect to each other.

Referring now to the use and operation of the device of my invention, when the conveyer pan line and reciprocating trough section 10 has been extended into the working place, preferably adjacent one rib thereof, and the extensible trough section 12 and corner pan 23 have been connected thereto, adjacent the working face, the loading pan 44 may be connected to said corner pan as in Figure 1, and if the working face is long enough, the loading pan 88 and a succession of similar loading pans may be connected to the free end of the loading pan 44 in parallel relation with respect to the working face and closely adjacent to the working face. Said corner pans and loading pans are put in this position just after the cutting operation, but before the shooting operation. The undercut coal is then shot down onto said corner and loading pans and the conveyer is started. Reciprocable movement of said corner pan and loading pans will cause the loose material to move along said loading pans in a direction towards said corner pan and onto and around said corner pan onto the extensible trough section 12. During this loading operation, the side board 56 is connected to the retreating side of said corner pan, to retain material thereon and

to permit material to be progressed onto said extensible trough section by means of said corner pan. When all of the material which has been shot down on said corner and loading pans has been loaded, the C-clamps 24, 24 may be loosened and said corner pan and extensible trough section and loading pans may be extended into the loose material to pick it up. Said C-clamps are again tightened after the extending operation. If desired, said loading pans may be disconnected from said corner pan and said corner pan may be advanced by itself into the broken down material, for cleaning up adjacent one corner of the room. These operations may be continued until the entire working place has been loaded out.

While I have herein shown and described one form in which my invention may be embodied, it will be understood that the construction thereof and the arrangement of the various parts may be altered without departing from the spirit and scope thereof. Furthermore, I do not wish to be construed as limiting my invention to the specific embodiment illustrated, excepting as it may be limited in the appended claims.

I claim as my invention:

1. In a face loading apparatus, a shaker conveyer trough line, a loading pan disposed at an angle to said trough line and having an advance edge adapted to slidably engage the ground, means for advancing said loading pan edgewise into the material it is desired to load, and means communicating with said loading pan and trough line for reciprocably driving said loading pan

35 from said trough line, said means also forming a means for conveying material from said loading pan into said trough line and having an advance edge slidably engageable with and adapted to pick up material from the ground.

2. In a face loading apparatus for shaker conveyers, a shaker conveyer trough line, a corner pan having connection with said trough line at one of its ends and reciprocably driven thereby, and being mounted for reciprocable movement about a fixed vertical axis, for conveying material around a corner, said corner pan having advance faces disposed at angles with respect to each other, for picking up material from the ground and transferring it onto said trough line.

3. In a face loading apparatus for shaker conveyers, a shaker conveyer trough line, a corner pan having connection with said trough line at one of its ends and reciprocably driven thereby, a mounting for said corner pan, for mounting said corner pan for reciprocable movement about a fixed vertical axis, spaced from said corner pan, for causing said corner pan to convey material around a corner, said corner pan having a rectilinear advance edge adapted to rest on and pick up loose material from the ground, upon reciprocation thereof.

4. In a face loading apparatus for shaker conveyers, a shaker conveyer trough line, a corner pan having connection with said trough line at one of its ends and reciprocably driven thereby, a mounting for said corner pan, for mounting said corner pan for reciprocable movement about a fixed vertical axis spaced from said corner pan, said corner pan having an advance edge adapted to rest on the ground and pick up loose material from the ground upon reciprocation thereof, and means connected with said mounting and guided for movement in a rectilinear path, for advancing said mounting and corner pan into the material

it is desired to load during operation of the conveyor.

5. In a face loading apparatus for shaker conveyers, a shaker conveyer trough line, a corner pan having connection with said trough line at one of its ends and reciprocated thereby, a mounting for said corner pan, for mounting said corner pan for reciprocable movement along the ground about a fixed vertical axis spaced from said corner pan, said corner pan having an edge adapted to rest on the ground and pick up loose material from the ground upon reciprocation thereof, and a loading pan disposed at an angle with respect to said trough line and having an advance edge adapted to slidably engage the ground and pick up material therefrom, said loading pan having connection with and being reciprocably driven by said corner pan.

6. In a face loading apparatus for shaker conveyers, a shaker conveyer trough line, a corner pan having connection with said trough line at one of its ends and reciprocably driven thereby, a mounting for said corner pan, for mounting said corner pan for reciprocable movement about a fixed vertical axis spaced from said corner pan, said corner pan having an edge adapted to rest on the ground and pick up loose material from the ground, upon reciprocation thereof, and a sectional loading pan having connection with and being reciprocably driven by said corner pan, said loading pan having an advance edge adapted to slidably engage the ground.

7. In a face loading apparatus for shaker conveyers, a shaker conveyer trough line, a corner pan having connection with said trough line at one of its ends and reciprocably driven thereby, a mounting for said corner pan, for mounting said corner pan for reciprocable movement about a fixed vertical axis spaced from said corner pan, said corner pan having an edge adapted to rest on the ground and pick up loose material from the ground, upon reciprocation thereof, and a sectional loading pan having an advance edge adapted to slidably engage the ground and having connection with and being reciprocably driven by said corner pan, means for advancing said corner pan into the material it is desired to load, and other means for advancing said loading pan upon advancing movement of said corner pan.

8. In a face loading apparatus for shaker conveyers, a shaker conveyer trough line, a corner pan having connection with said trough line at one of its ends and reciprocably driven thereby, a mounting for said corner pan, for mounting said

corner pan for reciprocable movement about a fixed vertical axis spaced from said corner pan, said corner pan having edges disposed at angles with respect to each other, adapted to rest on the ground and pick up loose material from the ground upon reciprocation thereof, a sectional loading pan having connection with and being reciprocably driven by said corner pan, said loading pan being reciprocably guided along its rear edge and slidably engaging the ground at its forward edge, and means for advancing said loading pan upon the advance of said corner pan.

9. In a face loading apparatus, a shaker conveyer trough line including an extensible trough section, a corner pan on the forward end of said extensible trough section and reciprocably driven thereby, a pivotal mounting for said corner pan, said corner pan having an advance edge adapted to pick up material from the ground, and means guided for rectilinear movement in a fixed path and forming a support for said mounting, for advancing said corner pan and extensible trough section.

10. In a face loading apparatus, a shaker conveyer trough line including an extensible trough section, a corner pan on the forward end of said extensible trough section and reciprocably driven thereby, a pivotal mounting for said corner pan, said corner pan having advance edges adapted to rest on the ground and pick up material from the ground, and means guided for rectilinear movement in a fixed path and forming a support for said mounting, for advancing said corner pan and extensible trough section, and other means extending along said extensible trough section for guiding said extensible trough section during advancing movement thereof.

11. In a face loading apparatus, a shaker conveyer trough line including an extensible trough section, a corner pan on the forward end of said extensible trough section and reciprocably driven thereby, a pivotal mounting for said corner pan, said corner pan having advance edges adapted to rest on the ground and disposed at angles with respect to each other for picking up material from the ground, and a loading pan having connection with and reciprocably driven by said corner pan, for loading material onto said corner pan at an angle with respect to said trough line, means for advancing said corner pan and extensible trough section, and other means for advancing said loading pan.

TIMOTHY F. McCARTHY.
